AUTOMATICALLY OPERATING CONTROL ARRANGEMENT FOR PAIRS OF ROLLERS

Hans Donath, Dresden, Germany, assignor to
VEB Muhlenbau, Dresden, Germany

Application October 19, 1954, Serial No. 463,261

5 Claims. (Cl. 241—35)

This invention relates to driving means for roller mills, and particularly to a freely acting differential gear for driving pairs of rollers in such mills and to a control arrangement for automatically regulating the roller speed.

As is generally known, pairs of rollers have been used for a long time in industry for a great variety of purposes. The pairs of rollers employed in roller mills are mounted in frames and have a grinding or pulverizing action on the material by being driven in opposite directions at different peripheral speeds. Pairs of rollers of this type are used in the milling industry, but also for grinding and pulverizing other materials, as wood, minerals or the like.

The invention refers to a roller mill particularly intended for grinding grain, and is particularly directed to a regulating device which automatically controls the speed of the rollers in dependence upon the turning moment ratio in the differential gear.

Banks of rollers were adjusted hitherto according to the experience and touch of an operator, i. e. by variable factors which could not be predetermined, and accordingly different results in regard to the quality of the product were obtained. This method was not economical, and tests have therefore been made to ascertain the variables involved in order to establish results which could be repeated. As a result of these tests roller mills have been developed, in which the control and regulation is effected by special devices. For instance, in order to obtain the differential velocities, infinitely variable speed transmissions have been used, in which either one roller or both have been regulated by a continuously variable speed control. In these cases the difference in speed, that is to say the ratio of revolution of the two rollers, was maintained constant at a certain value determined by calculation. The resultant effect is, however, not wholly dependent on relative speeds and absolute speeds, but also on the adjustment of the gap between the rollers. This adjustment also requires great experience and is effected by known apparatus according to tests. All known devices have been provided with measuring indicators, so that the parts could be adjusted according to factors obtained by tests or from experience to get the best grinding action with the least expenditure of power.

All these methods and devices have been found, however, to be complicated and difficult to watch, so that in practice they have not been generally adopted. In view of the necessity of constant readjustment, they required careful inspection in order to obtain the desired effect.

The invention eliminates these disadvantages and provides a roller mill, in which variations in power output are automatically regulated by the balancing of the power output of the slow and fast rollers. For the first time a completely automatic roller bank is constructed which is automatically put out of or into action only when the material to be ground is changed or the gap between the rollers has not been set properly. The adjustment of the gap is hereby facilitated and need only be effected once. In this may, a uniform, excellent quality of material with

2

highest throughput and least power consumption is obtained.

According to the invention, the roller mill is provided with a freely acting differential gear driving both rollers and comprising an epicyclic train which by way of a set of planetary wheels operates as differential gear and the construction of which is such that a reversely running element of the gear rotates at a speed equal to the sum of the speeds of rotation of the rollers. Owing to this arrangement, the difference in speed of the two rollers can be varied with certain limits, and the dimensioning of the elements of the gear determines the relative turning moments acting therein. Due to the provision of a differential gear and by the action of the planetary wheels, a completely automatic method of operation is obtained, as the adjustment and correct running of the pair of rollers is considerably facilitated. By this means the risk of over- or dead-milling is avoided and the displacement of passages considerably reduced. Further, it is possible with a differential gear to control the output automatically without the interposition of a regulating drive, for instance by directly driving the feed rollers from the slow running roller.

It is also now possible, by adjusting the free element of the drive, to obtain a corresponding reversal of the method of operation. By using a differential gear having a reversely running planetary wheel all requirements can be met for an automatic control of the pairs of rollers with a single or double stage planetary wheel arrangement. By this means a constant turning moment can be obtained.

The known automatic roller mills include only an automatic feed for the material to be ground, which prevent a reversal of movement of the material in the process and require an automatic closing up or movement apart of the rollers. This is very difficult to effect, and differences of output result from the constant gap between the rollers, which gives differences in grinding effect. Operation according to the invention is therefore wholly automatic.

In order to simplify the apparatus, a differential drive to two or more grinding shafts can be established, so that the rollers operate with the same turning moment, either being driven directly or in a step-down ratio.

The small space required for the differential gear allows it to be mounted within the rollers, so that increased milling capacity is obtained in the same space as hitherto.

By this invention, due to the increased speed of transmission of the driving and transmission elements, considerable material is saved in construction, and it is no longer necessary to use servo-motors, control elements or continuously variable speed drives. The invention provides a quiet drive which can be maintained for long periods with efficiency, as the differential drive can be wholly enclosed in an oil bath.

The arrangement of the invention is further described with reference to the accompanying drawings. In these, application of the invention is shown to a bank of rollers as used for grinding flour or like purposes. It is obvious that the invention can be applied to special requirements in other forms of banks of rollers by maintaining the principle of the invention. To explain the invention fully, the requirements for a mill drive are set forth in detail below. In the drawings

Figure 1 shows, by way of example, an arrangement of a differential gear driving a pair of rollers; and

Fig. 2 is a diagrammatic view of a roller bank particularly suitable for grinding flour.

In known manner, the two rollers 1 and 2 of a bank of rollers are disposed on parallel axes in bearings 3, so that in order to alter the gap 4 between the rollers, one roller is adjustable radially of the other. The rollers rotate with differing peripheral speeds, and the roller 1 acts as a

high speed cutting roller while the slower roller 2 feeds and grips the grain.

The roller 1 carries on its driving shaft a differential gear. This can be of any desired form, and any differential gear can be used where the torque applied to the driving shaft is normally transmitted to the two driven rollers in a predetermined ratio, regardless of the respective power outputs.

In the arrangement shown, the differential gear consists of a belt pulley 5 to which the drive is taken and which is fixed to a casing 7 having an internal ring gear 6. A sun wheel 9 is keyed on the shaft 8 of the fast roller 1, and simultaneously serves as a bearing for the pulley 5. A carrier 10 is mounted for rotation in the casing 7 about the stub shaft 8 and carries planet wheels 11 meshing simultaneously with the sun wheel 9 and the ring gear 6. The cylindrical boss of the carrier 10 mounted on the shaft 8 also serves as a bearing for the casing 7 to which the pulley 5 is fixed. The boss further carries a sprocket wheel 12 which is directly connected with the shaft 13 of the roller 2, for instance by a chain drive 14. The drive for the slow roller 2 is thereby stepped down. A belt pulley 20 is keyed to one end of the slow roller 2, which drives by means of a belt 22 the feed rollers 16 and 17 arranged above the rollers 1 and 2. Adjustable feedplates 18 of known type and construction are disposed above the two feed rollers to control the flow of material to said feed rollers 16 and 17. Should the grinding operation or the flow of material to be ground vary during operation of the machine, this will have an immediate effect on the relative speed of rotation of the two rollers 2 and 1 by reason of the differential gear. By the driving of the feed rollers 16 and 17 directly from the roller 2, the necessary change is effected in the speed of the feed rollers.

By this means the flow of material to be ground is varied until the turning moment has again become equal.

I claim:

1. An automatic speed control for a roller mill comprising in combination: a first rotatable roller, a second rotatable roller, a differential gear including a driving ele-

ment and two driven elements operatively connected with each other, and a speed reduction transmission, one of said driven elements being operatively connected with said first roller, the other driven element being operatively connected with the input end of said speed reduction transmission, and the output end of said speed reduction transmission being operatively connected with said second roller.

2. In an automatic speed control for a roller mill, as claimed in claim 1, at least one rotatable feed roller, and driving means operatively connecting said second roller with said feed roller for rotating the latter in dependence on the rotation of said second roller.

3. An automatic speed control for a roller mill, comprising in combination: a first rotatable shaft, a first roller rigid with said first shaft, a second rotatable shaft,

a second roller rigid with said second shaft, a carrier rotatably mounted on said first shaft, a plurality of planet gears rotatably mounted on said carrier, a sun wheel keyed to said first shaft, a driving housing having an internal gear, said housing rotatably mounted on said carrier, said planet gears being in mesh with said sun wheel and said internal gear, and a transmission operatively connecting said carrier with said second shaft for rotating the latter in dependence on a rotation of said carrier.

4. In an automatic speed control for a roller mill as claimed in claim 3, said transmission being in the shape of a speed reduction transmission for driving said second shaft at a speed lower than that of said first shaft.

5. In an automatic speed control for a roller mill as claimed in claim 3, at least one rotatable feed roller, and driving means operatively connecting said second shaft with said feed roller for rotating the latter in dependence on the rotation of said second shaft.
